(57) **CLAIM**

The ornamental design for a collapsible grocery bag, as shown and described.

DESCRIPTION

FIG. 1 is a perspective view of the collapsible grocery bag, showing the new design;

FIG. 2 is a front elevational view of the collapsible grocery bag thereof;

FIG. 3 is a rear elevational view of the collapsible grocery bag thereof;

FIG. 4 is a left side elevational view of the collapsible grocery bag thereof;

FIG. 5 is a right side elevational view of the collapsible grocery bag thereof;

FIG. 6 is a top plan view of the collapsible grocery bag thereof; and,

FIG. 7 is a bottom plan view of the collapsible grocery bag thereof.

The dash-dash broken lines depict portions of the collapsible grocery bag that forms no part of the claim.

The dash-dot broken lines depict a boundary of the claimed design and forms no part of the claim.

1 Claim, 6 Drawing Sheets
